UNITED STATES PATENT OFFICE

2,462,086

ELECTRON DISCHARGE DEVICE

John Heaver Fremlin and Stanley Gordon Tomlin, London, England, assignors, by mesne assignments, to International Standard Electric Corporation, New York, N. Y., a corporation of Delaware

Application March 26, 1945, Serial No. 584,818
In Great Britain December 6, 1943

Section 1, Public Law 690, August 8, 1946
Patent expires December 6, 1963

2 Claims. (Cl. 315—5)

1

The present invention relates to electric discharge devices of the electron velocity modulation type, and is concerned with tuning arrangements for the resonators of such devices, particularly for oscillation generators.

In radio communication systems, it is common practice to employ superheterodyne receiving circuits in which the local oscillator may have to be tuned over a relatively wide range. Such tuning is sometimes accomplished by a mechanical arrangement adjustable by hand, but when the frequency of the received waves varies rapidly, an automatic frequency control arrangement is necessary for keeping the oscillator in tune. Devices are known in which the tuning is effected electrically by varying the velocity of the electron beam, and these are particularly suitable for the application of automatic frequency control. However, at very short wave lengths it becomes difficult to make the resonators with a sufficient degree of precision to ensure that the mean frequency generated by the device is within the necessary limits. Suppose, for example, that the mean frequency to be received is 3,000 megacycles per second, and that this frequency may vary by $\pm 1\%$, or ± 30 megacycles per second. A suitable generating device may be electronically tunable over a range of ± 35 megacycles, and it will be evident that its mean frequency must be within the limits $3,000 \pm 5$ megacycles, on the assumption that the resulting intermediate frequency is small compared with the incoming frequency. This requires an accuracy of 5 parts in 3,000, and resonators cannot be made to fulfil such a requirement without the use of most expensive tools. However, an accuracy of $\pm 2\%$ can be easily achieved without specially accurate tools, and it is the principal object of the present invention to provide a simple means to enable such resonators to be adjusted during manufacture so that the desired accuracy of the mean generated frequency is obtained, so that no external trimming condenser or the like needs to be supplied.

According to the invention, an electric discharge device of the electron velocity modulation type comprises a system of one or more hollow resonators adapted to be excited by a beam of electrons projected therethrough, a screw being provided through the wall of a resonator and extending therewith for the purpose of adjusting the resonance frequency of the resonator by adjustment of the screw.

The invention also comprises a method of manufacturing an electric oscillation generator of

2

the electron velocity modulation type adapted to generate oscillations of a given frequency, which includes constructing a hollow resonator for the said generator adapted to resonate slightly above the given frequency, screwing a screw through the wall of the resonator, supplying oscillations at the given frequency to excite the resonator, connecting the resonator to a wave detector, and adjusting the screw to vary the portion extending inside the resonator until the detector indicates maximum excitation of the resonator, the said operations being carried out before assembling the resonator inside an enclosing envelope.

The invention will be explained with reference to the accompanying drawing in which:

Fig. 1 shows a perspective view, partly cut away, of a co-axial line resonator for a device according to the invention;

Figs. 2 and 3 show sectional views of two alternative forms of the invention;

Fig. 4 shows diagrammatically a test arrangement used in the adjustment of the resonance frequency of the resonator; and

Fig. 5 shows a perspective diagrammatic view of the complete device with the envelope removed, and with parts cut away to show details.

Fig. 6 shows a cross-sectional view of the device of Fig. 5 assembled in its envelope along the lines of the beam path.

In order to illustrate the invention, an electron velocity modulation type oscillator comprising a co-axial line resonator will be described. Such a device may be of the kind described in the specification of Patent No. 2,320,860. Fig. 5 gives a diagrammatic view of the device and Fig. 6 gives a cross-sectional view. The co-axial resonator is shown at 14, and an electron beam is fired through a slot 2 therein from a gun diagrammatically shown as consisting of a cathode 15 and control electrode 16, and is collected by a plate 17. The disc 18 is secured to the wall 1 of the resonator 14 and is sealed through the envelope 20 of the device, which envelope is shown in Fig. 6. Fig. 1 shows part of the resonator 14 to an enlarged scale to show the features of the invention clearly. 1 is the cylindrical wall of the resonator 14, and 2 is one end of the slot through which the electron beam is projected. The passage for the beam is defined by

parallel fins 3 attached to the wall 1, and by the parallel fins 4 attached to the central conductor 19 of the co-axial resonator 14, seen only in Fig. 5. These arrangements are all quite conventional and are explained in the above mentioned specification.

According to the invention, a screw 5 is screwed through the wall 1 and extends into the resonator in a region where the electric field is strong, and by adjustment of the screw from outside, the length which projects inside may be varied, thereby changing the resonance frequency of the resonator. The screw may be considered as distorting the electric field inside the resonator, or alternatively it may be thought of as introducing a variable capacity between the end of the screw and the adjacent fin 4, which capacity loads the end of the resonator, and therefore affects its resonance frequency.

If the wall of the resonator is too thin to provide a satisfactory support for the screw 5, a suitable nut or washer 6 may be brazed, or soldered, or otherwise secured to the outside surface of the wall 1 as shown in Fig. 2. Alternatively, a hole may be punched inwards as shown in Fig. 3 to provide bearing surfaces 7 into which suitable threads may be tapped to accommodate the screw.

When the position of the screw has been adjusted in the manner which will be described later, it is usually desirable that it should be rigidly fixed or otherwise sealed in order to prevent any subsequent alteration. This may be conveniently done by winding a turn of metallic tin wire or other solder round the screw where it joins the outside of the wall or washer 6; this wire will melt during the subsequent processing of the device and will secure the screw firmly in place. The arrangement shown in Fig. 3 is particularly suitable for this process, since the recess at 8 forms a convenient receptacle for the melted tin or solder, and a very neat and satisfactory joint results. The sealing or fixing material could alternatively be a cement or the like of any type suitable for use in a vacuum tube.

One method of setting the adjustment of the screw 5 is shown diagrammatically in Fig. 4. The assembly of the device is completed up to the point just before it is to be sealed into its envelope. Only the upper part of the resonator 14 is shown in Fig. 4, and it will be designed for a resonance frequency perhaps 2% above the final desired value, when the screw 5 is fully withdrawn from the inside of the resonator. The resonance frequency of different samples will thus be expected to vary over the range 0 to 4% above the final desired value. A co-axial transmission line 9 is connected by an adapter 10 to the open end of the resonator, and is connected at its other end to a generator, not shown, supplying oscillations at a frequency higher than the desired final resonance frequency by an amount equal to the frequency drift which occurs in the finished device during the warming up period. The inner conductor of the co-axial line 9 terminates in a short probe 11 for the purpose of exciting the resonator. A small hole 12 is provided in the wall 1 of the resonator 14 opposite the screw 5 for transferring the oscillations to a crystal detector unit 13 tuned to the generator frequency. The screw 5 is adjusted until a maximum reading is obtained on a suitable indicator, not shown, connected to the crystal detector. Then the resonance frequency of the resonator is closely equal to the desired value. The hole 12 may finally be closed, though this is often unnecessary if the hole is small, and the device is assembled inside its envelope and the usual pumping and processing operations are performed. During the heating for out-gassing of the device, the screw 5 becomes soldered in place as already explained.

The resonator should, of course, be properly annealed before the adjustment is made, otherwise distortion is likely to take place during the subsequent processing.

The most suitable size of the screw 5 depends on a number of factors, such as the equivalent capacity of the resonator, the mean resonance frequency, and the desired range of adjustment. The total range available should be rather greater than is actually necessary, because adjustment becomes very critical if the end of the screw gets too close to the fin 4. In a particular case where the wave-length was 10 cm, and a range of adjustment of 5% was desired, a standard 6 BA screw was found to be suitable.

It will be evident that although a device with a co-axial resonator has been illustrated, a similar screw arrangement could be used to adjust other types of resonators employed in electron velocity modulation devices, which are not necessarily oscillation generators. For example, in devices of the type employing two separate resonators with a drift tube between, each of the said resonators could be provided with a screw through the wall projecting into a strong part of the field, for adjusting the resonance frequency.

What is claimed is:

1. An electric discharge device of the electron velocity modulation type comprising a hollow resonator of the coaxial line type having an open end and a closed end, means adjacent said resonator for projecting a beam of electrons through said resonator for exciting said resonator, and a single adjustable screw screwed through the outer line at a point adjacent said open end of said coaxial line type resonator and having a portion adapted to extend into the interior towards the inner conductor thereof whereby the resonator is tuned to a desired frequency.
2. A method of manufacturing an electric oscillation generator of the electron velocity modulation type adapted to generate oscillations of a given frequency which includes constructing a hollow resonator of the coaxial-line-type for the said generator adapted to resonate slightly above the given frequency, screwing a screw through the outer line of said resonator, locating fusible material in the neighborhood of the joint between the screw and the outer line, supplying oscillations at the given frequency to excite the resonator, connecting the resonator to a wave detector, adjusting the screw to vary the portion extending inside the resonator towards the interior line thereof until the detector indicates maximum excitation of the resonator, assembling the resonator in an enclosing envelope, and heating the resonator to melt the fusible material for the purpose of sealing the joint.
